UNITED STATES PATENT OFFICE.

ALFRED B. WALES, OF WHITMAN, MASSACHUSETTS, ASSIGNOR TO B. FLEIGEL COMPANY, OF BOSTON, MASSACHUSETTS, A CORPORATION OF MASSACHUSETTS.

EDGE-TRIMMER ATTACHMENT FOR SEWING-MACHINES.

959,275.

Specification of Letters Patent.

Patented May 24, 1910.

Application filed April 24, 1909. Serial No. 491,932.

To all whom it may concern:

Be it known that I, ALFRED B. WALES, a citizen of the United States, residing at Whitman, county of Plymouth, and State 5 of Massachusetts, have invented an Improvement in Edge-Trimmer Attachments for Sewing-Machines, of which the following description, in connection with the accompanying drawing, is a specification, like 10 characters on the drawing representing like parts.

This invention relates to an under trimming attachment for sewing machines and particularly to a work guide adapted to be 15 associated with such attachment. These under trimming attachments are used for trimming the edge of one of two parts which are to be sewed together so that the trimmed edge will come even with the edge 20 of the other part. As an example of the way in which such edge trimming attachments are used, I will refer to the step in the process of the manufacture of shoes by which the lining is sewed to the upper. 25 After a lining of a shoe is cut, it has sewed to that portion of the edge thereof at the top of the shoe a strip of leather called a top facing, and then the lining with the top facing attached is sewed to the upper by a 30 line of stitching which runs close to the edge of the upper. During this process of sewing the lining to the upper, it is customary to trim the edge of the lining and top facing so that said edge will come even with 35 the edge of the upper, such trimming being done by means of the edge trimming attachment for the sewing machine.

My invention has for its object to provide a novel guide adapted to engage the edge 40 of the upper and guide the latter so that the line of stitching will be at the proper distance from the edge, which guide does not interfere in any way with the use of the ordinary edge-trimming attachment.

45 My improved guide is sustained independently of the trimming knife and is so supported that it will follow the movements of the knife and will guide the material equally well whether the lining or other 50 part to be trimmed is thick or thin.

Other advantages of my invention will be more fully hereinafter described and the novel features of the invention will be pointed out in the appended claims.

55 Figure 1 is a view of a portion of the bed

of a sewing machine showing the needle bar, needle and presser foot, and also showing my improved guide associated with the trimming knife; Fig. 2 is a top plan view with the needle bar and presser foot omitted; Fig. 60 3 is a view similar to Fig. 2 showing a modified form of the invention; Fig. 4 is a section on the line $x-x$, Fig. 2; Fig. 5 is a section on the line $y-y$, Fig. 3. Figs. 6 and 7 are sectional views on the lines $a-a$ and $b-b$, Fig. 2.

The parts which are old and form no part of my present invention are the bed 3 of the sewing machine, the needle bar 4 with the needle 5, the presser wheel 6 which runs 70 on and holds the work in position, and the reciprocating trimming knife 7. This trimming knife 7 is of usual construction, it having the depending flange 72 at one end which is formed with the cutting edge 45 75 that acts on and cuts the edge of the material to be trimmed. Said trimming knife is pivotally sustained on a stud 8 rising from the plate 9, and said knife is provided with the resilient shank 10 which has an 80 aperture therein that is adapted to set over a projection 11 carried by an oscillating arm 12 that is also pivotally mounted on the stud 8. The arm 12 has rigid therewith a depending yoke 73 in which operates the usual cam 85 (not shown) by which a vibrating motion is given to the arm and thereby to the trimming knife in a manner well known to those skilled in the art. The trimming knife is formed with the portion 44 that extends 90 beyond the cutting edge 45 and under which the edge to be trimmed passes.

The two pieces to be sewed together are shown at 15 and 16 and for the sake of illustration I will refer to these as the upper and 95 the lining of the shoe. The upper 15 is of the proper shape and needs no trimming, but the lining 16 when applied to the upper has the edge 41 projecting beyond the upper, which edge has to be trimmed so that it will 100 come even with the edge 42 of the upper. During the operation of sewing the upper and the lining together by a line of stitching 17, the edge 41 of the lining to be trimmed passes under the portion 44 of the trimming 105 knife 7 and the cutting edge 45 of the knife acts during its oscillation to trim the edge 41 even with the edge 42 in a manner well known to those skilled in the art and which requires no further explanation here. When 110

the lining is sewed to shoe uppers, it is not necessary to trim the lining around the lower edge of the upper but only around the top and front edge thereof. It is, therefore, customary to disengage the spring shank 10 from the arm 12 and to swing the knife into its inoperative position, such as shown in dotted lines Fig. 2, at such times as it is not desired to use the trimming knife.

10 My improvement consists in providing a guide 20 adapted to engage the edge 42 of the upper and thereby properly guide said upper so that the line of stitching 17 will be situated at a uniform distance from the edge 42. This guide 20 is sustained independently of the knife 7 and is adapted to be at all times in proper position for guiding the upper whether the knife 7 is in operative position for cutting or is thrown out 20 of operation. In the form of the invention shown in Fig. 2, this guide is carried by a resilient shank 21, one end of which is secured to the plate 9. The under face of the guide rests on the top of the knife, and said 25 guide is provided with the extension 25 which has the curved under face 26. When the knife is in its operative position the guide rests on the knife and acts to guide the edge 42 as will be obvious. When the knife 30 is thrown into its inoperative position, as shown in dotted lines Fig. 2, the guide still remains in position to properly guide the material, and the resiliency of the shank 21 holds the under surface of the guide below 35 the level of the top surface of the work rest 48 so that said guide acts to accurately guide the work. When the knife is swung back into its operative position, the upper face of the knife engages the curved surface 26 and 40 forces the guide upwardly sufficiently to permit the knife to pass thereunder. My improved guide, therefore, is one which does not require any adjustment when the knife is thrown from one position to the other.

45 The spring shank 21 may be secured to the plate 9 in a variety of ways without departing from my invention. As herein shown, I have provided the plate with a keeper 22 under which the end 50 of the 50 shank 21 may be inserted. This end 50 of the shank is shown as having a headed stud 52 rising therefrom on which is sustained a thumb-piece 53, a spring 54 being confined within a recess formed in the thumb-piece 55 and situated beneath the head of the stud. The upper face of the keeper is provided with a slot 55 of a size to receive the stud, and said slot is enlarged at 56 to receive the portion 57 of the thumb-piece. When the 60 lower portion of the thumb-piece occupies the enlarged portion 56 of the slot, the guide is locked in position, but by raising the thumb-piece against the spring 54, thereby to withdraw the portion 57 from the enlarged portion of the slot, the shank may be

withdrawn from the keeper. The keeper is secured to the plate by means of screws 60, and I prefer to make the apertures in the keeper through which the screws pass slightly larger than the screws, so that said keeper may be adjusted somewhat.

In Figs. 3 and 5 I have shown an embodiment of my invention wherein the guide has a somewhat different shape from that shown in Figs. 1, 2 and 4. In Figs. 3 and 5, 75 the guide is sustained by a resilient shank 21^a, the end of which is secured to a block 70 that is carried by the plate 9. The under surface of the guide shown in Figs. 3 and 5 is curved upwardly at both sides at 64 and 80 65. The curved surface 64 is equivalent to the curved surface 26 on the guide shown in Figs. 1 and 2, and it permits the knife to be swung into its operative position without adjusting the guide. The curved surface 65 85 is provided so that in sewing a lining to the upper the stay piece in the back of the lining or any other thickened portion of the lining may readily pass under the guide.

Having fully described my invention, what 90 I claim as new and desire to secure by Letters Patent is:—

1. In a sewing machine, the combination with stitching mechanism and a movable edge trimmer adapted to be moved from its 95 operative to its inoperative position, of a guide for the edge of the work situated above the edge trimmer and in contact therewith when the latter is in operative position, and a resilient shank independent from the 10 edge trimmer for supporting said guide, said trimmer being movable relative to the guide.

2. In a sewing machine, the combination with stitching mechanism and a movable edge trimmer, of a resiliently-supported 10 guide for the edge of the work situated above and in contact with the trimmer when the latter is in its operative position, said guide being supported independently from the trimmer and operating to guide the work 11 when the trimmer is in its inoperative position.

3. In a sewing machine for sewing together two layers of material, the combination with stitching mechanism including a 11 needle and an under-edge trimmer adapted to trim the edge of the under layer at a point opposite the needle, of a resiliently-supported guide for the edge of the upper layer situated above and in contact with the 1 trimmer when the latter is in operative position.

4. In a sewing machine for sewing together two layers of material, the combination with stitching mechanism including a 1 needle and an under-edge trimmer arranged to trim the edge of the under layer at a point opposite said needle and movable from its operative to its inoperative position, of a guide for the upper edge of the work resili- 1

ently supported independently from the trimmer and adapted to engage said edge of the work whether the trimmer is in its operative or its inoperative position.

- 5 5. In a sewing machine, the combination with stitching mechanism including a needle, of an under-edge trimmer for trimming the edge of the under piece of the two pieces being sewed together, of a guide for the edge 10 of the upper piece situated above and in contact with the trimmer when the latter is in operative position, and means to resiliently support said guide whereby when the trimmer is swung into its inoperative position 15 the guide will assume a proper position to guide the edge of the work.

6. In a sewing machine, the combination

with stitching mechanism and a vibrating edge trimmer, of a stationary guide situated above and resting on said trimmer when 20 the latter is in operative position, a resilient arm sustaining said guide, the latter having a beveled under face to engage the top of the edge trimmer, and means independent from the edge trimmer for supporting the 25 arm.

In testimony whereof, I have signed my name to this specification, in the presence of two subscribing witnesses.

ALFRED B. WALES.
